UNITED STATES PATENT OFFICE.

EUGENE OSWALD, OF THE UNITED STATES NAVY.

MEANS FOR RECOVERING SUBMARINE BOATS.

No. 856,096.

Specification of Letters Patent.

Patented June 4, 1907.

Application filed May 18, 1906. Serial No. 317,478.

To all whom it may concern:

Be it known that I, EUGENE OSWALD, of the United States Navy, a citizen of the

United States, and a resident of the city of 5 New York, borough of Manhattan, county and State of New York, have invented a new and Improved Means for Recovering Submarine Boats, of which the following is a full, clear, and exact description.

10 This invention is an improved means for the recovery of lost submarine boats, designed to place the location of the submarine with certainty in both day and night, permitting communication with those imprisoned therein and obtaining a hawser attached to the boat without the use of divers.

When a submarine boat is sent below the surface, she is generally, when in practice, accompanied by some tender; and as a rule 20 arrangements are made with the attending vessel to follow her up while running entirely submerged. This is made possible by the course to be steered and the speed to be made known by the tender while so running, 25 but at the same time the location of the boat while below is only a matter of conjecture, as it is impossible to be sure of her position with certainty, at any time. Should the submarine boat during her submerged run, 30 meet with an accident, there would be nothing to indicate the place at which it happened, and it would be necessary to employ divers to ascertain this, consuming much valuable time before assistance could be rendered.

35 The object of this invention is to overcome these disadvantages by a simple device which can be installed on boats already built or now building, at a small cost.

To this end one embodiment of my invention 40 consists of a buoy seated over a receptacle in the boat and held thereon by means operable to release it from the interior of the boat. This buoy has attached at its lower end and coiled about it a strong light line of 45 sufficient length to reach the surface of any ordinary depth of water. The free end of the line is connected with a wire cable resting in brackets attached to the outside of the submarine, which in turn is connected to a 50 chain bridle of sufficient strength, as is also the cable, to pull the boat out of the mud and raise it above the surface of the water.

The buoy carries an electric light, rendering it visible at night, and contact screws for 55 a telephone, which are wired to the interior

of the submarine, where it is connected with any suitable electric generator and a telephone.

Reference is to be had to the accompanying drawings forming a part of this specification, in which similar characters of reference indicate corresponding parts in all the figures.

Figure 1 represents the submarine boat at the bottom of a body of water with my improvements attached, showing the position of the buoy after it has been released; Fig. 2 is a longitudinal, central, vertical section of the buoy; Fig. 3 is a fragmentary, longitudinal section through the shell of the submarine, disclosing how my improvements are attached, and Fig. 4 is a plan view of the buoy.

The numeral 1 indicates a submarine boat of the usual construction, having bands 2 75 and 2^a respectively fore and aft riveted about it, which carry any suitable attaching means, as for example, ring bolts 3 and 3^a. Attached to the ring bolts 3 and 3^a is a chain bridle 4, which in turn is connected at its 80 center to a wire cable 5 spirally wrapped about the deck of the boat and held in brackets 6 having notched faces for holding the cable against accidental displacement but admitting of its ready release when pulled 85 vertically upward. These brackets 6 are riveted or otherwise secured to the boat radially of the conning tower and spaced at substantially equal distances apart. In practice it is also preferable to store the 90 chain bridle in brackets or fix it in such a manner that danger of it puncturing a hole in the boat due to the rolling of the latter, will be eliminated.

Near the conning tower a receptacle 7 is 95 provided in the boat, shaped as a frustum of a cone with a projecting seat 8 around its upper edge. In this seat is fixed a rubber gasket 9 adapted to form a water-tight joint over the receptacle when a buoy 10 is seated 100 over it. The buoy 10 is preferably made up of two cones riveted together, with a flange 11 projecting over their meeting edges, to the under face of which a gasket 12 is secured to contact with the gasket 9.

105 The bottom of the buoy has a block 13 in its apex, in which a threaded recess *a* is formed for engaging a screw 14 operable from the interior of the boat. This screw passes through the center of the receptacle 7 110

and is provided with a bracket 15 to guide it and a stuffing box 16 to insure a water-tight fit about the screw.

Around the screw 7 and concentric with it projects a pot 17 flared at its outer end to receive the socket of the buoy and prevent a small, strong line 18 coiled about in the receptacle 7 from coming in contact with it. This line as clearly shown in Fig. 3, is attached to the free end of the cable 5 and passes down an aperture in the gaskets and flange of the buoy, and after being coiled about in the receptacle 7 is tied in a ring at the socket end of the buoy.

15 At the top of the buoy a lamp globe 19, surrounded by a steel cage which protects it, is fixed. Wires 22 passing to the globe and to telephone contact screws 23 near the globe, run through the buoy passing outwardly 20 through a ring at its socket end and then upwardly through an aperture in the gasket and flange where they are coiled into a cup or recess 24 with the free ends thereof passing to the dynamo in the submarine and to a telephone.

25 When accident happens to the submarine, the buoy is released by turning the screw 14 to disengage it from its seat, permitting the water to rush in the receptacle 7 and the buoyant force thereof to raise the buoy rapidly to the surface, carrying with it the line 18 and electric wire 22. The buoy is of such color that it can be easily detected in the day time as well as by night owing to the illumination of the electric light, thus enabling the location of the submarine to be determined with certainty.

When the buoy is picked up by the tender or other craft, the men in the submarine can 40 be communicated with by attaching a small, portable telephone with the contact screws 23. By hauling on the line 18 the wire cable 5 is released from the notches in the brackets 6 and readily brought to the surface; and as 45 it is customary to send an attending vessel with the submarine while on practice, which as a rule is fitted with a derrick, the boat, in case of accident, could easily be recovered without loss of time or life.

50 Should the submarine be with a fleet, the powerful cranes for lifting steam launches would be of great service in order to bring her to the surface.

Having thus described my invention I 55 claim as new and desire to secure by Letters Patent;

1. In combination with a submarine boat,

bands having ring bolts at each end thereof, a chain bridle connecting the ring bolts, a cable connecting the bridle at its center, 60 notched brackets spaced about and secured to the deck of the boat, said cable being adapted to be loosely engaged in the notches of said brackets, a receptacle in the boat, a buoy seated over the receptacle, a line connecting the buoy and cable adapted to be coiled in the receptacle, a screw passing through the receptacle and engaged in the buoy for releasing it from its seat, telephone connections and an electric light carried by 65 the buoy, and wires connecting them carried in a recess in the boat and passing therein.

2. In combination with a submarine boat, a buoy adapted to be released therefrom, a line connected to the buoy, a cable connected 75 to the line, a bridle connecting the cable with the submarine, and means on the submarine for carrying the line and cable.

3. In combination with a submarine boat, a buoy adapted to be released therefrom to 80 rise to the surface of the water, an electric light and telephone connections carried by the buoy, wiring for connecting the light and telephone connections to the interior of the submarine, a line connected to the buoy, a 85 cable connected to the line, means connecting the cable to the submarine, and means for holding the cable in coiled relation to the deck of the submarine, for the purpose described.

4. In combination with a submarine boat, a receptacle therein, a buoy seated over the receptacle, means operable from the interior of the submarine for releasing the buoy from the seat, a line connecting the buoy adapted 95 to be stowed in the receptacle, and brackets spaced about the conning tower of the submarine having notches therein, and a cable connecting the line with the submarine and coiled about in the notches of the brackets, 100 for the purpose described.

5. In combination with a submarine boat, a bridle attached thereto, a buoy seated on the boat and adapted to be released therefrom, and means connecting the buoy and 105 bridle together.

In testimony whereof I have signed my name to this specification in the presence of two subscribing witnesses

EUGENE OSWALD.
